UNITED STATES PATENT OFFICE

2,030,309

CURTAIN FIXTURE

Marie Martinez, Memphis, Tenn.

Application January 22, 1934, Serial No. 707,691

4 Claims. (Cl. 156—23)

This invention relates to improvements in curtain fixtures, and has for its object to provide a curtain pole bracket fixture hingedly mounted upon a window frame, whereby the brackets may be let down when desired to receive or release a curtain pole or rod within reach of a person standing on the floor.

Another object of the invention is to provide a curtain fixture including a U-bar bracket member adapted to be hingedly mounted intermediate of a window frame and means whereby the same may be instantly raised or lowered for the purpose of attaching or detaching a curtain rod or for dusting the same, and the top of a curtain

15 on the rod.

A still further object of the invention is to provide a curtain pole bracket fixed to the central part of a window frame, and so arranged that a curtain pole attached thereto may be

20 instantly raised to the top of the window and secured there, or let down to within convenient

reach of a person on the floor.

With the above and such other objects in view as may hereinafter more fully appear, I have

25 invented the device shown in the accompanying

drawing in which:

Figure 1 is a front elevational view of a window, embracing my invention;

Figure 2 is a side elevational view thereof;

30 and

Figure 3 is a perspective view of the fixture removed from the window frame.

Like reference characters indicate like parts, throughout the following specification and in the 35 several views in the drawing in which 1 indicates a window frame, to the central part 2 of which is pivotally mounted a U-shaped fixture 3, through eyes 4 and 5, at the terminals 6 and 7 of the parallel arms 8 and 9, of said U-member. 40 At approximately the points 12 and 13, where the arms 8 and 9 meet, the cross head 14, are carried brackets 15 and 16 to receive a remov-

able pole 17 for a curtain or the like 18. Attached, as at 19, to the head bar 14, is one end of a cord 20, which is threaded through an eye or pulley 21, secured at the upper end 22 of said window frame 1, and from which member 21 5 the cord drops to the lower portion of the frame 1, and is secured to a hook or other similar device 22 attached to the lower portion 23 of said frame, whereby the fixtures may be held in raised position, as indicated in Figure 1 of the drawing. By releasing cord 20 the fixture may be caused to swing down to a position, as indicated in Figure 2 of the drawing, in order that the head 24 of the curtain 18 and the pole and fixture may be dusted, or the pole released from 15 or attached to the fixture by a person standing on the floor. By drawing down on the knot 25 on the free end of the cord 20, the fixture may be quickly drawn to its raised position and held there by securing said knot in hook 22. 20

Having described my invention, that which I claim to be new, and desire to procure by Letters Patent is:

1. A curtain fixture consisting of a single piece of material formed U-shape, and terminating at 25 each end in pivot eyes, and hooks formed on the parallel arms of said U-member.

2. A curtain fixture consisting of a single piece of material formed U-shape, and terminating at each end in pivot eyes, and hooks formed on 30 the parallel arms of said U-member, adjacent the upper end thereof.

3. A curtain fixture consisting of a single piece of material formed U-shape, and terminating at each end in pivot eyes, and hooks formed on 35 the parallel arms of said U-member, adjacent the upper end thereof, the cross head of said U-member having an eye at one end thereof.

4. The device, as claimed in claim 3, and means connected with said eye whereby the fixture may 40 be raised and lowered.

MARIE MARTINEZ.
